ADOLPHUS S. DENNIS, OF LAKEWOOD, OHIO, ASSIGNOR TO UNDERWOOD TYPEWRITER COMPANY, OF NEW YORK, N. Y., A CORPORATION OF DELAWARE.

TYPE-WRITING MACHINE.

1,180,479.

Specification of Letters Patent. Patented Apr. 25, 1916.

Application filed July 30, 1913. Serial No. 781,921.

To all whom it may concern:

Be it known that I, ADOLPHUS S. DENNIS, a citizen of the United States, residing in Lakewood, in the county of Cuyahoga and State of Ohio, have invented certain new and useful Improvements in Type-Writing Machines, of which the following is a specification.

This invention relates to means for variably assembling and subsequently advancing superposed work-sheets in typewriting machines having revoluble platens.

One of the principal objects of the invention is to provide a simple and efficient device which may either be used as a readily applied attachment to existing machines, or at least which will involve nothing beyond simple and inexpensive changes in such machines.

The work-sheets are provided with rows of perforations along their side borders, and they are laid face down upon a suitable support, and there impaled upon gage pins by means of said perforations. The gage pins extend in rows from front to rear along the sides of said support; although one row of gage pins may be omitted in some cases.

The leading edges of the sheets are nearest to the revoluble platen of the typewriter; the sheets in fact occupying about the same positions as they do when they are being inserted into a typewriter in the ordinary manner, the leading edge of the sheet being presented to the rear of the platen, the sheet being inverted so that the leading edge is at the bottom for this purpose, while the rear side of the sheet faces the operator.

On the face of the sheet the gaging perforations along its side are numbered, these numbers indicating the places for the lines of writing, and being usually at intervals equal to the line-spacing movements of the platen.

In practising the present improvements, the sheets are also provided with numbers on their rear faces, so that each perforation is numbered the same on both the front and rear face of the sheet. The numbers on the rear side appear in their natural positions when the sheet is being laid upon the gage pins, the numbers on the rear side running from the leading edge to the final edge, but each number being inverted in relation to the corresponding number on the front face of the sheet, so that the numbers on both

sides of the sheet are easily read in their natural positions whether the operator is looking at the front or rear side thereof.

From the foregoing, it will be understood that the operator needs only to lay the sheets upon the support or sheet-board, very much as he would in inserting the sheets in an ordinary typewriter, and that he may place any sheet in desired relation with any other sheet, by studying the numbers of the gage perforations.

After inserting the necessary carbon sheets, the operator withdraws the gage pins and advances the sheets to the platen without disturbing their relative positions, until they reach the position for receiving the first line of writing, which will fall upon the desired lines of the various sheets.

The advancing of the assembled sheets to the platen is preferably effected by turning an endless web upon which they are assembled, which serves as a sheet-supporting board while they are being assembled. This web may run over rolls, and may be connected to the platen by any suitable gearing, as for instance a sprocket and chain gearing, so that the surface speed of the web will equal the surface speed of the platen. The assembled sheets are held on the web by rolls, so that the sheets are properly advanced to and around the platen, whereupon they are controlled by the usual feed rolls which run upon the bottom of the platen.

The rolls which coöperate with the web are releasable to give clearance for assembling the sheets; and preferably a single motion both releases the rolls and restores the gage pins to protruding positions; a reverse motion causing a simultaneous retraction of the pins and movement of the rolls to positions to coöperate with the web. The same arrangement as to rolls and pins may be made at each side of the web.

Other objects and advantages will herein-after appear.

In the accompanying drawings, Figure 1 is a perspective front view of the present improvements applied to the paper carriage of an Underwood front-strike typewriting machine. Fig. 2 is a view to show the special feed rolls retracted and the gage pins protruded at the left-hand side of the feed web; the several sheets being shown impaled upon the gage pins. Fig. 3 is a view similar to Fig. 2, but showing the pins

withdrawn and the feed rolls thrown into working positions. Fig. 4 illustrates the movement of the controlling lever from the Fig. 3 position toward the Fig. 2 position. Fig. 5 is a front sectional diagrammatic elevation of the invention in its preferred form, showing both feed rolls and gage pins at each side of the sheet assembling board. Fig. 6 shows one of the work-sheets having perforation indicating numbers on each of the front and rear faces thereof. Fig. 7 is a sectional side elevation showing the gage pins retracted and the special feed rolls in working positions. Fig. 8 is a perspective view showing the mounting of one of the sets of gage pins. Fig. 9 is a perspective illustrating the superposition of two work-sheets. Fig. 10 is a view similar to Fig. 5, but omitting one set of gage pins, and showing both sets of special rolls cast off to clear the assembling board for placing the sheets thereon.

The Underwood typewriting machine usually comprises types 1 which strike upon the front side of a platen 2 mounted by means of an axle 3 and ends 4, 5, of a platen frame, said ends connected by a paper shelf 6, and the axle usually having hand wheels 7 for rotating the platen. The platen frame 25 is usually mounted upon a carriage, a part of which is seen at 8. Fig. 1, and a line-space lever 9 operates a slide 10 and pawl 11 to turn the line-space wheel 12 which is provided upon the platen axle.

The work-sheets 13, 14, 15 are laid upon an extension of the paper shelf 6, this extension in the form of a web 16 which runs over upper and lower pulleys or rolls 17, 18 which are journaled by means of axles in a pair of side frames 19, 20 extending upwardly and rearwardly from the ends of the paper shelf 6 and connected by tie-rods 21, 22. The frame is supported upon the paper shelf 6 by means of downwardly extending tongues 23 which rest upon a transverse rod 24 usually fixed to the platen frame and extending along behind the upper rear side of the paper shelf. The tongues at their lower ends extend beyond this rod 24 and bear up against the rear of the paper shelf. Shoulders or lugs 25 on the tongues rest upon the rod 24 to support the side frames.

Along the outer borders of the work-sheets are evenly-spaced perforations 26 by which the sheets are maintained in any desired relationship upon gage pins 27 which extend in a row along one or both sides of the sheet-supporting web 16, said pins standing upon a bar 28 which is carried upon the bar 19, Fig. 1, and also upon the bar 20, Fig. 5.

The holes 26 are numbered as shown in Fig. 1, on the rear sides of the sheets, and will be easily read by the operator when

the sheet is viewed in the position in which it is naturally presented to the platen, namely, leading edge down and with its rear side to the operator. These perforation numbers are therefore read from the leading edge to the opposite edge of the sheet, but stand upside down when the sheet is placed with its leading edge at the top. These numbers, however, correspond to the numbers seen at 29 on the front of the work-sheets, so that the operator, by regarding the rear numbers, may effect any desired relative position of the sheets.

After placing the necessary carbons between the superposed sheets, the operator swings inwardly projecting handles 30 and 31, thereby swinging down clamping or feeding rolls 32, 33 upon the sides of the sheets, and also withdrawing the gage pins 27. It will be noticed at Fig. 8 that the gage pin bar 28 is mounted by means of arms 34 upon a rock shaft 35 at the rear end of which is an arm 36 that is engaged by a pin 37 projecting from an arm 38 that rises from a rock shaft 39 on which the arm 30 is fixed, so that when the arm 38 swings to the right the bar 28 is depressed and the pins 27 withdrawn from the perforations in the work-sheets.

Each of the pressure rolls 32, 33 is carried in a frame 40 swiveled at 41 between opposite arms 42 which are fixed upon a hub 43, the latter capable of limited rotation upon the rock shaft 39 or 44, as the case may be. In order that each roll 32 may bear 95 against the paper independently of the other rolls, each is provided with an individual spring 45 connected at one end to a collar 46 on the rock shaft and at the other end engaging one of the arms 42. The independent movement of the arms 42 is limited by a pin 47 projecting from the rock shaft 39 through a slot 48 in the hub 43. The rock shaft 39 is held in its effective position by means of a spring detent 49 engaging a notch 100 50 in the hub of arm 38. It will be understood that the structure at the right-hand side of the frame corresponds to that at the left-hand side throughout, so that the description of one suffices for both, although in some cases the gage pins at one side of the structure may be omitted, together with the corresponding bar 28 and shaft 35. A spring 51 is coiled around the gage pin shaft 35 to hold the pins 27 up in normal 105 protruded positions and to return them to such positions when the operator swings the handle 30 to the left to withdraw the feed rolls 32.

It will be observed that the upper and lower feed rolls 32 are directly opposed to the upper and lower pulleys 17, 18 over which the web 16 runs. An intermediate feed roll 52 is provided between the reaches of the web to coöperate with the middle roll 110

32 to feed forward the assembled work-sheets.

At Fig. 5 the parts are in positions for the advance of the sheets to the platen; the gage pins at both sides having been withdrawn and all the surface feed rolls 32, 33 being held down to clamp the sheets upon the web. The operator now grasps the handle 7 to rotate the platen in the usual manner, and a chain 53 extending from the sprocket 54 on the platen to a sprocket 55 on the web roll 18, causes the web to be advanced at the same surface speed as the platen, and hence the sheets are advanced by the coöperation 15 of the web with the rolls 32, 33 until they are brought under the control of the platen, and the usual forward and rear feed rolls 56, 57, which run upon the under side of the platen. After the sheets are brought under 20 the control of the rolls 56, 57, the rolls 32 and 33 need no longer be depended upon, and the sheets are now advanced by turning the hand wheel 7 to be brought into position to receive the first line of writing. There- 25 after the writing may proceed line by line in the usual manner. If desired, the operator may then reverse the direction of rotation of the platen, and the web 16, to return the sheets to positions to be impaled 30 upon the pins again, and for this purpose the rolls 32, 33 may be lifted sufficiently to permit the introduction of the sheets between the same and the web without causing the pins 27 to protrude above the side plates 19, 35 20. As soon as the sheets have been retracted far enough, the rolls 32, 33 may be cast off and the pins projected, and the sheets may then be pressed down upon the pins, and if desired one or more sheets may 40 be withdrawn and other sheets substituted preparatory to advancing the re-assembled sheets to the platen. The retraction of the sheets in the manner stated is not, however, necessary in all cases. The movement of 45 the frames 40 about their pivots 41 is limited by pins 60 on the frames extending into openings 61 in the arms 42.

It will be seen that by a very simple appliance the operator is enabled to place the 50 sheets in any desired relationship to one another and then to preserve such relationship while the sheets are being advanced around the under side of the platen in the usual manner into position to receive the 55 writing. To connect the two shafts 39 and 44 to work in unison, there may be provided a transverse rock shaft 62 having on its ends beveled pinions 63, 64 to mesh with segments 65, 66 on the rock shafts.

60 Variations may be resorted to within the scope of the invention, and portions of the improvements may be used without others.

Having thus described my invention, I claim:

65 1. In a typewriting machine, the combi-

nation with a revoluble platen, of a frame, an endless web on said frame arranged to provide a support on which to adjust a work-sheet while the web is at rest, means to drive the web, and holding means to extend over the sheet and hold it against the web in its adjusted position thereon and cause it to be advanced with the web and thereby fed to the platen, said holding means arranged to be withdrawn to permit 75 adjustment of the work-sheet on the web.

2. In a typewriting machine, the combination with a revoluble platen and a paper shelf at the introductory side of the platen, of a frame supported on said shelf, an endless work-sheet feeding web on the frame, forming, when at rest, a support on which to adjust work-sheets, and means to hold superposed work-sheets in different relative positions of adjustment on said web, the lat- 85 ter having its upper face extending substantially in alignment with the paper shelf and terminating at the rear end of said shelf.

3. In a typewriting machine, the combination with a revoluble platen, of a series 90 of pins arranged to engage perforations in the side margins of work-sheets, and upon which the work-sheets may be variously positioned at different degrees of advancement by means of said marginal perforations, and means to withdraw said pins and free the work-sheets without changing the positions of the work-sheets.

4. In a typewriting machine, the combination with a revoluble platen, of a series 100 of pins upon which work-sheets may be positioned by means of marginal perforations, means to feed the work-sheets to the platen, and means to withdraw said pins so that the work-sheets may be fed to the 105 platen.

5. In a typewriting machine, the combination with a revoluble platen, of two series 110 of pins, one at each end of the platen on which work-sheets may be positioned by means of marginal perforations, said sets of pins being parallel and extending away from the platen, and means to withdraw said pins and permit the work-sheets to be fed to the platen.

6. The combination of a support for a work-sheet, a series of pins by which the work-sheet may be positioned on said support by means of marginal perforations, means to withdraw said pins, and mechanism for holding the work-sheet in position on said support after the pins are withdrawn.

7. The combination of a support for a work-sheet, a series of pins by which the work-sheet may be positioned on said support by means of marginal perforations, means to withdraw said pins, mechanism for holding the work-sheet in position on said support after the pins are withdrawn,

and means to feed the work-sheet forward on said support to the platen.

8. In a typewriting machine having a revoluble platen, the combination of a support for a work-sheet, a series of pins or studs to engage marginal perforations in the work-sheet, and thereby position the work-sheet on said support before it is carried to the platen, feed rollers movable into position to hold the work-sheet, and means to drive said feed rollers and feed the work-sheet to the platen.

9. In a typewriting machine, the combination of a revoluble platen, a separate support for a work-sheet, a row of positioning pins whereby the work-sheet may be positioned on said support by means of marginal perforations, said row extending at right angles to the platen, and means for moving all of said pins as a unit into and out of position to engage the work-sheet.

10. The combination with a support having a flat supporting surface for a work-sheet, of a series of pins positioned to extend through marginal openings along the edge of the work-sheet, pressure rollers movable into and out of engagement with a work-sheet at said surface to hold the sheet against said support, and means for simultaneously withdrawing said pins and moving said rollers against the work-sheet.

11. In a typewriting machine, the combination with a revoluble platen, of a work-sheet carrier at the introductory side of the platen, feed rolls in position to support said carrier and a work-sheet thereon, and pressure rolls above the feed rolls and work-sheet, and movable into and out of engagement with the work-sheet on said carrier, and cooperating with the feed rolls and carrier to advance the work-sheet.

12. In a typewriting machine, the combination with a revoluble platen, of a paper shelf at the introductory side of the platen and extending upwardly and rearwardly therefrom, feed rolls, an endless web extending around said rolls and presenting a support for a work-sheet substantially in alinement with the paper shelf, means to drive said rolls, pressure rollers located above said web, and movable into and out of position to bear against the work-sheet supported on said web.

13. In a typewriting machine, the combination with a revoluble platen, of an endless work-sheet conveyer on which work-sheets may be arranged at the introductory side of the platen, means to drive the conveyer and advance the work-sheets to the platen, pressure rolls to run on the work-sheets and hold them on the conveyer, and means to shift said rolls away from the conveyer to permit the placing and adjustment of the sheets on the conveyer.

14. In a typewriting machine, the combination with a revoluble platen, of an endless work-sheet conveyer located at and movable with the work-sheet toward the introductory side of the platen, pressure rolls to run upon and hold the work-sheet on said conveyer, gearing between said conveyer and the platen to advance said conveyer at the same speed as the periphery of the platen when the latter is rotated, means to shift the said rolls away from the conveyer to permit adjustment of the work-sheet on the conveyer, and means to hold the work-sheet in adjusted position while the rolls are away from the conveyer.

15. In a typewriting machine, the combination with a revoluble platen, of pulleys at the introductory side of the platen, an endless work-sheet conveyer extending over said pulleys and movable toward the introductory side of the platen, a sprocket and chain drive between the platen and one of said pulleys, and means to engage the work-sheet to hold it on said conveyer and cause it to be fed to the platen, said means shiftable to clear the conveyer and permit the manual placing and adjustment of the work sheet on the conveyer.

16. In a typewriting machine, the combination with a platen, of a support for a work-sheet at the introductory side of the platen, a rock shaft parallel with the side edge of the work-sheet, rollers parallel to the platen and supported by said rock shaft, said rollers positioned to bear against the work-sheet on said support, and means to rock said rock shaft and swing said rollers away from said support.

17. In a typewriting machine, the combination with a revoluble platen, of a frame at the introductory side of the platen, means to support a work-sheet on said frame, rock shafts located at opposite ends of the platen and parallel with the side edges of the work-sheets, rollers carried by said rock shafts and adapted to bear against the work-sheets with their axes parallel to the platen axle, and means for rocking said shafts and carrying the rollers supported thereby into and out of engagement with a work-sheet.

18. In a typewriting machine, the combination with a revoluble platen, of a frame at the introductory side of the platen, means to support a work-sheet on said frame, rock shafts located at opposite ends of the platen and parallel with the side edges of the work-sheets, rollers carried by said rock shafts and adapted to bear against the work-sheets with their axes parallel to the platen axle, means for rocking said shafts and carrying the rollers supported thereby into and out of engagement with a work-sheet, a series of pins adjacent each rock shaft to position a work-sheet by means of marginal openings in the work-sheet, and means to withdraw each series of pins when the corresponding

rock shaft is operated to move its rolls into engagement with the work-sheet.

19. In a typewriting machine, the combination with a rotatable platen, of a frame at the introductory side of the platen, rollers parallel with the platen and journaled in the ends of said frame, an endless work-sheet carrier extending over said rollers and forming a support on which the work-sheets may be arranged with their leading edges adjacent the platen, means to hold the work-sheets on the carrier in said position, and gearing between said carrier and the platen for driving the sheet-carrying portion of the carrier toward the platen when said platen is rotated, and thereby advancing the work-sheets to the platen.

20. In a typewriting machine, the combination with a rotatable platen, of a frame at the introductory side of the platen, rollers parallel with the platen and journaled in the ends of said frame, an endless conveyer extending over said rollers, gearing between said conveyer and the platen for driving the conveyer when the platen is rotated, rock shafts parallel with the edges of said conveyer, and rollers carried by said rock shafts to swing into and out of position to coöperate with said first-named rollers in holding the work-sheet on said conveyer.

21. The combination of a support for a work-sheet, a series of pins in position to enter perforations in the marginal edge of a work-sheet and thereby position the latter on its support, a frame carrying said pins and comprising a rock shaft, a second rock shaft parallel with said first-named shaft and carrying pressure rollers movable into and out of position to hold the work-sheet, and interlocking means between said rock shafts whereby when the pressure rollers are moved into operative position the said pins are simultaneously withdrawn.

22. The combination of a support for a work-sheet, a series of pins in position to enter perforations in the marginal edge of a work-sheet and thereby position the latter on its support, a frame carrying said pins and comprising a rock shaft, a second rock shaft parallel with said first-named shaft and carrying pressure rollers movable into and out of position to hold the work-sheet, an arm on said first-named rock shaft, and means on said second-named rock shaft to engage said arm and move said pins out of operative position when said rollers are moved on to the work-sheet.

23. The combination of a platen, a support for a work-sheet, a bar carrying a series of pins in position to engage marginal openings in the work-sheet and thereby position the work-sheet on said support, means to swing said bar and thereby withdraw said pins from the work-sheet, and a sheet-holding and advancing device to carry the

sheet to the platen after the pins are withdrawn.

24. The combination with a platen, of a separate sheet-feeding support for a work-sheet, devices for positioning the work-sheet on said support prior to its introduction to the platen, devices separate from the platen for holding the work-sheet in such position, means for moving said positioning and holding devices alternately into and out of engagement with the work-sheet, and means for advancing said support and thereby feeding the sheet thereon to the platen when the sheet is released from the positioning devices.

25. The combination with a platen, of a support for a work-sheet, a rock shaft, a frame on said rock shaft, a row of positioning pins extending at right angles to the platen and carried by said frame, means to swing the rock shaft into and out of position to project said pins above the face of said support, and a device to advance the sheet from said support to the platen.

26. In a typewriting machine, the combination with a rotary platen, of pulleys, a web extending around said pulleys and presenting a substantially flat support for a work-sheet, said support located at the introductory side of the platen and arranged to permit the work-sheets to be placed thereon while the web is at rest, means to engage the work-sheets while in said position and square them with the platen, means to hold the work-sheets on the web to be advanced thereby to the platen, and means for driving said web.

27. The combination with a revoluble platen, of a sheet-engaging device by which work-sheets may be collated and positioned relatively to the platen by means of perforations along their side edges before the sheets are carried to the platen, said sheets being releasable from said collating device to permit the sheets to be carried to the platen, and means for preserving the adjustment of the sheets when released and carrying them to the platen.

28. The combination with a revoluble platen, of a sheet-engaging device by which work-sheets may be collated and positioned relatively to the platen by means of perforations along their side edges before the sheets are carried to the platen, said sheets being releasable from said collating device to permit the sheets to be carried to the platen, means for preserving the adjustment of the sheets when released, and means connected to the platen for advancing the sheets to the platen while the relative adjustment of the sheets is preserved.

29. In a typewriting machine, the combination with a revoluble platen, of a frame adjacent to said platen, an endless web on said frame, means to engage the side edges

- of work-sheets as they are laid upon said web, means to release the sheets from said engaging means and also to hold the sheets upon said web to be advanced thereby to the platen, and means to drive said web and thereby feed the work-sheets to the platen.
30. In a typewriting machine, the combination with a revoluble platen, of a series of pins upon which work-sheets may be variously collated by means of marginal perforations before the sheets are carried to the platen, means to release said sheets from said pins, and means to preserve the adjustment of the sheets in advancing to the platen.
31. In a typewriting machine, the combination with a revoluble platen, of a series of pins upon which work-sheets may be variously collated by means of marginal perforations, before the sheets are carried to the platen, means to release said sheets from said pins, means to preserve the adjustment of the sheets, and means operated by the platen in its rotation to advance the work-sheets to the platen.
32. In a typewriting machine, the combination with a revoluble platen, of means for variously collating work-sheets preparatory to their introduction to the platen, and means for holding said sheets in their relative positions during their advance to the platen, said collating and holding means operating together, one to release and the other to engage the work-sheets, to maintain the adjustment of said work-sheets while being carried to the platen.
33. In a typewriting machine, the combination with a revoluble platen, of means for variously collating work-sheets preparatory to their introduction to the platen, means for holding said sheets in their relative positions during their advance to the platen, said collating and holding means operating together, one to release and the other to engage the work-sheets, to maintain the adjustment of said work-sheets while being carried to the platen, and means connected to the platen to advance the sheets thereto.
34. In a typewriting machine, the combination with a revoluble platen, of a movable work-sheet support, means for positioning a work-sheet thereon while the support is at rest and prior to the introduction of the work-sheet to the platen, means for holding the work-sheet upon said support, and means operating with the rotation of the platen, to advance said support, thereby causing it to carry the work-sheet to the platen.
35. In a typewriting machine, the combination with a revoluble platen, of a movable work-sheet support, means for variously positioning work-sheets thereon while the support is at rest and prior to the introduction of the work-sheets to the platen, means

for holding the work-sheets in their relative positions upon said support, and means operating with the rotation of the platen, to advance said support, thereby causing it to carry the work-sheets in succession to the platen.

36. In a typewriting machine, the combination with a revoluble platen, of a frame, an endless work-sheet supporting web on said frame arranged to permit work-sheets to be placed thereon at the introductory side of the platen while the web is at rest, means to square a work-sheet with the platen when placed on said web, means to drive said web to feed the work-sheet to the platen, and holding means movable into engagement with the sheet to cause it to move with the web, said holding means arranged to be withdrawn to permit the positioning of the work-sheet on the web.

37. In a typewriting machine, the combination with a revoluble platen, of a frame, an endless supporting web for work-sheets carried by said frame, means to gage the sheets on the web while the web is at rest, means for holding the work-sheets on said web to advance continuously therewith, and means for driving said web to thereby feed the work-sheets to the platen.

38. In a typewriting machine, the combination with a revoluble platen and a paper shelf, of a frame extending upwardly from said shelf, a work-sheet support carried by said frame and movable toward and from said paper shelf, to convey work-sheets thereto for introduction to the platen, means for gaging a work-sheet on said support while the latter is at rest, means for holding the work-sheet in its gaged position upon said support to advance therewith, and means movable with the rotation of the platen to drive said support, and thereby feed the work-sheet to the platen.

39. In a typewriting machine, the combination with a revoluble platen, of a frame, an endless carrier for work-sheets in the form of a web arranged to form a support on which a work-sheet may be placed at the introductory side of the platen while the web is at rest, means for holding the work-sheet on said carrier, said means shiftable to clear the web and permit the placing of the work-sheet thereon and means for driving said carrier to thereby feed the work-sheet to the platen.

40. In a typewriting machine, the combination with a revoluble platen, of a series of pins for adjustably engaging work-sheets by marginal perforations therein to variously position said work-sheets relatively to the platen for introduction thereto, and means for releasing said pins so that the work-sheets may then be fed to the platen.

41. In a typewriting machine, the combination with a revoluble platen, of a series

- of engaging pins, occupying a fixed position relatively to the platen advance, to adjustably assemble a number of work-sheets by means of marginal perforations therein in 5 different positions relatively to the platen, for introduction thereto, and means for releasing said pins so that the work-sheets may be fed successively to the platen in the order of their respective relative positions.
- 10 42. In a typewriting machine, the combination with a rotary platen, of a work-sheet carrier arranged to form a support on which work-sheets may be placed and arranged, means to square with the platen a number 15 of work-sheets placed on said support in superposed relation with the leading edge of one sheet in advance of another, means to maintain the work-sheets in their adjusted position on the carrier, and means to 20 drive the carrier and cause it to advance the work-sheets to the platen while retaining them in said relation.
43. In a typewriting machine, the combination with a rotary platen, of means to 25 square with the platen a number of work-sheets placed in superposed relation at the introductory side of the platen with the leading edge of one work-sheet in advance of the leading edge of another, a sheet carrier, means to effect a driving connection 30 between the work-sheets and said carrier after the work-sheets have been thus arranged, and means to drive the carrier and advance the work-sheets to the platen while 35 they are held in their relative positions of adjustment.
44. The combination with a rotary platen, of a work-sheet carrier forming, when at rest, a support for the adjustment thereon 40 of a work-sheet at the introductory side of the platen, work-sheet squaring means arranged to engage the side margin of a work-sheet placed on said carrier with said margin extending laterally beyond the carrier, 45 means to maintain the work-sheet in driving engagement with the carrier to be fed thereby to the platen, and means to drive the carrier.
45. The combination with a rotary platen, of a work-sheet carrier forming, when at rest, a support for the adjustment thereon 50 of a work-sheet at the introductory side of the platen, work-sheet squaring means arranged to engage the side margin of a work-sheet placed on said carrier with said margin extending laterally beyond the carrier, feed rolls arranged to overlie the carrier and work-sheet and to hold the latter on the carrier, and means for withdrawing the feed rolls to permit the work-sheet to be positioned on the carrier. 55
46. The combination with a rotary platen, of an endless carrier arranged to form a support for work-sheets placed thereon at the introductory side of the platen while the 60 carrier is at rest, a series of holding pins extending along one side of the carrier in position to engage perforations in the side margin of a work-sheet placed on the carrier with said margin projecting laterally 65 beyond the carrier, means to withdraw said holding pins to permit the sheet to be advanced with the carrier, means to retain the sheet in its adjusted position on the carrier, and means to drive the carrier and advance 70 the sheet to the platen.
47. In a typewriting machine, the combination with a platen, of means to gage a series of work-sheets placed successively in 75 position to be fed to the platen in superposed relation and at different positions of advancement in line-feeding direction, an endless carrier, means movable into and out of holding position for holding the sheets on the carrier to be advanced thereby 80 to the platen, means to withdraw said gag- 85 ing means to permit the sheets to be ad- vanced, and means to cause said holding means to move into operative position con- comitantly with the withdrawal of the gag- 90 ing means.

ADOLPHUS S. DENNIS.
